UNITED STATES PATENT OFFICE.

HENRY A. WISE WOOD, OF NEW YORK, N. Y., ASSIGNOR TO THE WOOD NEWSPAPER MACHINERY CORPORATION, OF NEW YORK, N. Y., A CORPORATION OF VIRGINIA.

TAIL-CUTTING DEVICE FOR TUBULAR PLATES.

Original application filed March 11, 1915, Serial No. 13,733. Renewed May 16, 1919. Serial No. 297,565.
Divided and this application filed December 11, 1919. Serial No. 344,235.

To all whom it may concern:

Be it known that I, HENRY A. WISE Wood, a citizen of the United States, residing at New York, in the county of New York and 5 State of New York, have invented a new and useful Tail-Cutting Device for Tubular Plates, of which the following is a specification.

This is a division of my Patent No. 1,332,- 10 531, granted March 2, 1920, on casting and finishing apparatus curved stereotype printing plates on an application originally filed March 11, 1915, Ser. No. 13,733, renewed May 16, 1919, Ser. No. 297,565.

15 This invention relates to the finishing of curved stereotype printing plates and particularly those plates known as tubular plates in which each one constitutes a complete cylinder, with the exception of a narrow gap the width of the margin.

The principal objects of the invention are to provide means whereby ribs formed on the plates during the casting operation will be shaved on the inside during the ejection 25 of the cast plate from the mold; to provide means whereby during the shaving operation the plate will be backed up by the surface against which it is cast, at least at a point opposite the shaving blade, and will 30 have the matrix on which it is cast located between it and this backing surface, so that the printing surface cannot be marred; to provide means for cutting the tail from the 35 plate after it is ejected without first giving it any motion except that required for ejecting it, and to provide improvements in the mechanism for accomplishing these results.

The invention also involves other features of invention which will appear hereinafter.

40 Reference is to be had to the accompanying drawings in which—

Fig. 1 is a side view of a finishing apparatus constructed in accordance with this invention;

45 Fig. 2 is a rear elevation of the same;

Fig. 3 is a plan;

Fig. 4 is a sectional view of the tail cutter on line 4—4 of Fig. 3, and

50 Fig. 5 is a horizontal sectional view on the line 5—5 of Fig. 2, showing the casting box itself in plan to illustrate the shaving operation.

Although capable of use for other forms

of castings, the invention is particularly designed for making tubular stereotype plates, 55 as has been stated above. As ordinarily constructed, these plates are made in a mold having a cylindrical core and it is necessary to remove them from the casting box by hand, turning the core over into horizontal 60 position for that purpose. They are then placed in a boring machine in which the inner surface of the plate is turned smooth in order to fit the plate cylinder of the printing press. This boring operation 65 is slow because the entire inner surface of the plate must be dressed off by it. It has not been possible to cast these tubular plates with circumferential ribs, or finishing strips, 70 on their inner surfaces because, obviously, they could not be removed from the core in that case without serious and expensive complications. The use of longitudinal ribs is also prevented by the fact that this would make the plates weak between the ribs and 75 furthermore the turning of the interior surfaces of longitudinal ribs would be a more delicate operation than is the case with the circumferential ribs on the ordinary semi-cylindrical plate.

80 In order to solve these difficulties according to said original patent I make the plate with one or more helical ribs on its interior surface extending from end to end. This is accomplished by using a core having one or more helical grooves on its exterior throughout its entire length. This not only has the result of permitting the finishing of the interior of the plate by a simple operation, because only a small amount of metal 85 has to be removed, but it also has several other advantages. In the first place while the plate is being ejected in this way the shaving operation can be performed simply by the use of a blade on the core itself. In 90 this way manual handling of the casting is avoided and in fact the time usually taken for removing the casting and putting it into the finishing or boring machine is saved. Furthermore the matrix can be left in contact with the plate while it is being ejected and finished, thus protecting the plate from 95 contact with any hard metal on its printing surface.

100 By the use of this invention, furthermore, 105 the tail cutting operation can be performed

in a comparatively simple manner without handling the plate between the casting and the tail cutting operations. Although I prefer to use mechanism for ejecting the plate by power, it is to be understood that it can be turned out by hand in a similar manner according to this invention.

In the form of the invention shown in the drawings, a cylindrical casting box 10 is 10 shown mounted in vertical position.

The top of the core 13 is made of concave conical shape for receiving the chips made by a shaving blade 18 mounted on the core.

The casting box is provided with a vertical longitudinal groove 21 which is filled by the matrix bar 22. It will be noticed that this matrix bar projects a short distance above the top of the casting box.

Mounted on and supported by the wall of 20 the casting box 10 are bearings 24 for a driving shaft 25 on which is loosely mounted a driving pulley 26. A clutch 27 is provided for connecting this pulley in an obvious manner with the shaft and driving the 25 shaft. A treadle 30 is provided for operating the clutch and starting the shaft to operate. On this shaft is a worm 28 meshing with a worm wheel 29 which is fixed to the lower end of the core that projects below the 30 casting chamber so that upon the connection of the pulley with the shaft this worm wheel and core will be rotated. The teeth of the clutch are arranged slanting on one side and the core can be driven in one direction only, 35 so as to eject the plate.

The shaft 25 by means of mitre gears drives a vertical shaft 31 which in turn drives a horizontal shaft 32 mounted on a bracket 34 which is cast with the casting box 40 10 and extends upwardly therefrom. On this shaft 32 is a worm 33 for driving a worm wheel 35. This worm wheel is provided with a hub 36 and is capable of rotating independently of the hub. On the 45 hub is a spring-pressed pin 37 for entering a socket 38 in the wheel 35 so that the hub will be rotated with the wheel. The pin has a bevel flange 39 on the upper end thereof. Above the hub of the worm wheel is a sliding cam 40 having a beveled edge adapted to engage under the head of the pin and raise the pin. This cam is supported on spring rods 41 mounted in bearings on the bracket 34 and these spring rods normally 50 force the cam into the position shown in Figs. 1 and 3 in which it raises the pin 37 out of engagement with the socket 38 in the worm wheel. For the purpose of withdrawing this cam a shaft 42 is provided on the bracket having arms 43 which engage pins 44 on the rods 41. One of the arms on the shaft 42 is shown as being connected by a chain or the like 45 with a hand hold 46.

By pulling down on the chain the rods 41 60 are withdrawn and the pin 37 is allowed to

descend so that upon the next rotation of the worm wheel the hub thereof will be carried around with it.

Journalled in bearings 47 on the bracket 34 is a vertical shaft 48. This shaft supports and rotates with the hub member 36 so that when this is in rotation the shaft also will rotate. On this shaft is a loose intermediate gear 49 which is driven by a gear 50 on the shaft 31 and meshes with a planetary pinion 51 on a vertical shaft 52. This shaft is carried by a carrier 53 rotatable with the shaft 48. This shaft 52 is provided with a tail cutter 54 in the form of a circular saw. This is located at such a point that it will engage in a space on the plate when the same is elevated into the dotted line position shown in Fig. 1 and will then rotate around the same and cut off the tail. A circular ring 55 is provided on the lower surface of the carrier 53 to receive the tail end of a plate as it is elevated, guiding it into proper position, and holding it. Hooks 57 are provided for supporting the slug after it is severed.

The operation of the device is as follows:—When the plate is properly cooled the treadle 30 is depressed, causing the clutch to engage and the shaft 25 to revolve. This of course revolves the core. The first effect of this revolution of the core is to cause the plate to rise in the casting box longitudinally as described in my original patent above identified. The rotation of the core forces the plate out longitudinally. During this operation the shaving blade 18 on the top of the core shaves off the rib or ribs on the inside of the plate, leaving the interior surfaces of these ribs in the form of a perfect cylindrical surface. By this means 100 it will be seen that only a small body of metal is being removed at any one time. Consequently, little power is required. Furthermore, the operation of removing the plate from the mold also causes the plate to 105 be shaved on the interior and brought to a proper diameter for fitting the printing plate cylinder of the press. The shavings from this operation pass down the conical upper end of the core and out through the 110 central passage therethrough so that they are taken care of by gravity.

The reason for extending the casting bar up above the top of the mold will be seen from what has been stated as it causes the 115 plate to be held against rotation even when it rests on the top of the core.

The matrix and pouring sheet are raised from the mold with the plate, and consequently, during the shaving operation, the 120 plate is still backed up by the pouring sheet and matrix and the type surface of the plate never comes into contact with a metallic holding surface during the entire shaving 125 operation but remains in contact with the 130

matrix against which it was cast. Thus all chance of injuring the plate on its printing surface is eliminated. The pouring sheet and matrix are removed by the operator at the proper time.

As soon as the plate is entirely raised from the casting box so that it rests on top of the core as shown in dotted lines in Fig. 1, the operator pulls the chain 45 and then the constantly rotating worm gear 35 imparts its rotation to the hub 36 and shaft 48. This causes the tail cutter to rotate around the plate one revolution and sever the slug. The slug is then held by the hooks 57 until the plate is removed from beneath it. It will be understood that while the plate is rising the tail engages the guide ring 55 and the tail cutter is left in position to encircle the plate and remove the slug. At the end of a complete revolution the flange 39 on the top of the pin 37 again encounters the cam 40 which after being released by the hand of the operator automatically springs back to operative position.

It will be seen, therefore, that by this means the plate is removed from the mold without separating the parts of the mold and consequently without any hand operation. I am aware of the fact however, that the core can be rotated by hand to eject the plate, and even to shave it without departing from the scope of this invention. During the ejection of the plate the interior is shaved to the proper cylindrical shape and size without the loss of time, and without transferring the plate from the mold to a shaving machine. When the plate is completely ejected it is left in position for the tail cutting operation without any manual manipulation of the plate and the cutting of the tail is performed automatically after the mechanism is started. It is stopped at the end of a revolution automatically leaving the tail cutter in position for commencing the next operation.

Although I have illustrated and described only a single form of the invention and shown the machine as being driven by power I am aware of the fact that many modifications can be made therein and that it can be operated by hand and applied to the finishing of other kinds of castings without departing from the scope of the invention as expressed in the claims. Therefore, I do not wish to be limited in these respects, but what

I do claim is:

1. The combination with a support for a cast plate, and means for ejecting the cast plate axially from said support, of a gear, means connected with the first named means for constantly rotating said gear when the first named means is in operation, a hub loosely mounted on the gear, means for connecting said hub with the gear for rotating the hub with the gear, a shaft in alignment

with the axis of the support and rotatable with said hub, a tail cutter carried by said shaft at a distance from its center and adapted to rotate therewith, and means connected with said ejecting means for rotating said tail cutter on its own axis while it is rotating around the plate.

2. The combination of a gear, means for constantly rotating said gear, a hub loosely mounted on the gear, means for connecting said hub with the gear for rotating the hub with the gear, a shaft rotatable with said hub, a tail cutter carried by said shaft at a distance from its center and adapted to rotate therewith, and means for rotating said tail cutter on its own axis while it is rotating around with the shaft.

3. In a tail cutting device, the combination of a gear, a hub loosely connected with said gear, yielding means adapted to connect the hub with the gear once during each rotation of the latter, means for rotating the gear, means for automatically disengaging the connecting means after a rotation of the gear, a tail cutter, means operated by said hub for swinging said tail cutter around in a circle, and independent means for rotating said tail cutter on its own axis while it is moving around in a circle.

4. In a tail cutting device, the combination of a wheel provided with a socket, means for rotating said wheel, a hub loosely mounted with respect to said wheel and having a spring-pressed pin adapted to enter said socket whereby the wheel will rotate the hub, a slideable cam mounted on said hub having means for withdrawing said pin after a rotation of the hub, manually operated means for withdrawing the cam to release the pin, a carrier rotatable with said hub, a tail cutter mounted on said carrier at a distance from the center, and external means for rotating the tail cutter on its own axis.

5. In a tail cutting device, the combination of a wheel provided with a socket, means for rotating said wheel, a hub loosely mounted with respect to said wheel and having a spring-pressed pin adapted to enter said socket whereby the wheel will rotate the hub, means for withdrawing said pin after a rotation of the hub, a tail cutter mounted at a distance from the center, and external means for rotating the tail cutter on its own axis.

6. In a tail cutting device, the combination with means for feeding a cylindrical plate axially, a carrier, a guide for receiving the end of the plate and holding it in central position, means for rotating said carrier about the axis of the plate, a tail cutter carried by said carrier at a distance from the center, and means for rotating said tail cutter on its own axis as the plate rotates.

7. The combination with a vertical sup-

port for a cast plate, of a shaft, means on the top of the support for preventing the plate from turning, a tail cutter mounted above the support, and means connected with said shaft for rotating said cutter on its own axis and also rotating it about the axis of the plate while said plate is supported at the top of the support.

8. The combination with a vertical box, of means for ejecting a cast plate from the box, means for simultaneously shaving out the interior of the plate, and means connected with said shaving means for cutting the tail from the plate after it has been ejected.

9. The combination with a support for a cast plate, of a shaft, means at the end of the support for preventing the plate from turning, a tail cutter, located at a distance beyond said means, means for moving the plate along the support into registration with said tail cutter, and means connected with said shaft for rotating said cutter on its own axis and also rotating it about the axis of the plate while said plate is on the support.

10. In a tubular plate finishing machine, the combination with means for moving a tubular plate in an axial direction, of means for progressively shaving out the interior of the plate a short length at a time as the plate moves along.

11. In a plate finishing machine the combination of a rotary shaving blade extend-

ing only throughout a part of the length of a plate to be finished, with means for simultaneously rotating the blade and moving the plate longitudinally to progressively shave its interior.

12. In a plate finishing mechanism, the combination with means for supporting a cast plate in position for cutting the tail therefrom, means for feeding a curved plate into said supporting means, means for shaving out the interior of the plate progressively as it engages said supporting means.

13. In a machine for finishing a tubular cast plate having a helical rib on its inner surface, the combination of rotary means for engaging said rib and feeding the plate along axially thereby, with means for simultaneously shaving said rib.

14. The combination with a support for a cast plate, of a shaft, means at the end of the support for preventing the plate from turning, a tail cutter, and means connected with said shaft for rotating said cutter on its own axis and also rotating it above the axis of the plate while said plate is on the support, and hooks for supporting the severed tail while the plate is being removed from the support.

In testimony whereof I have hereunto affixed my signature.

HENRY A. WISE WOOD.
